UNITED STATES PATENT OFFICE

107,549

DESIGN FOR AN AUTOMOBILE BODY

Robert Rogers, Detroit, Mich.

Application October 7, 1936, Serial No. 65,191

Term of patent 3½ years

To all whom it may concern:

Be it known that I, Robert Rogers, a citizen of the United States, residing at Detroit, in the county of Wayne and State of Michigan, have invented a new, original, and ornamental Design for an Automobile Body, of which the following is a specification, reference being had to the accompanying drawing, forming part thereof.

Figure 1 is a perspective view of the front and one side of an automobile body showing my new design.

Figure 2 is a fragmentary perspective view of the rear and a portion of the opposite side thereof.

The side opposite that appearing in Figure 1 is substantially the same as shown.

I claim:

The ornamental design for an automobile body as shown and described.

ROBERT ROGERS.
